CLAIM

The ornamental design for a projectile launching device as shown and described.

DESCRIPTION

FIG. 1 is a front elevation view of a projectile launching device.

FIG. 2 is a right side elevation view of a projectile launching device of FIG. 1.

FIG. 3 is a left side elevation view of a projectile launching device of FIG. 1.

FIG. 4 is a back elevation view of a projectile launching device of FIG. 1.

FIG. 5 is a top plan view of a projectile launching device of FIG. 1.

FIG. 6 is a bottom plan view of a projectile launching device of FIG. 1.

FIG. 7 is a perspective view of a projectile launching device of FIG. 1; and,

FIG. 8 is another perspective view of a projectile launching device of FIG. 1.

Features shown in the Figures in broken lines are portions of a projectile launching device that form no part of the claimed design.
